UNITED STATES PATENT OFFICE.

RALPH OSBORN, OF RANDOLPH, NEBRASKA.

LAMP.

1,379,279.

Specification of Letters Patent. Patented May 24, 1921.

Application filed May 29, 1919. Serial No. 300,642.

To all whom it may concern:

Be it known that I, RALPH OSBORN, a citizen of the United States, residing at Randolph, in the county of Cedar and State of Nebraska, have invented certain new and useful Improvements in Lamps, of which the following is a specification.

This invention relates to lamps, and more particularly to an electric lamp utilizing a battery as its energizing or exciting supply source, and an object of the invention is to provide a relatively slight portable lamp which may be conveniently carried about and one which is particularly designed for use in residences where kerosene lamps are generally used, it being particularly adapted for use as a bedroom lamp, for enabling the user to have sufficient light to prepare for retiring without the inconveniences contingent with the use of a kerosene lamp, such as the lighting of the lamp by matches, keeping the lamp properly supplied with fuel, the inconvenience of procuring the match when the user does not have one, as well as several other inconveniences incidental with the use of kerosene lamps.

A further object of the invention is to provide an electric lamp as specified which comprises a relatively large base adapted to support the lamp in an upright position, which base has the battery inclosing cell of the lamp detachably connected thereto to provide a top plate for the lamp which carries a slidable switch mechanism for controlling the energizing of the light bulb which is carried by a suitable socket supported by the battery inclosing shell or housing.

A further object of the invention is to provide a lamp as specified which may be used in lieu of an ordinary flashlight for a dark room light in photographic work, and one in which a new battery may be easily placed when the original therein becomes spent or exhausted.

Other objects of the invention will appear from the following detailed description, taken in connection with the accompanying drawing, forming a part of this specification and in which drawing:

Figure 1 is a vertical section through the improved lamp.

Fig. 2 is a top plan of the lamp.

Fig. 3 is a fragmentary section through the top of the lamp, taken on a line at right angles to the section illustrated in Fig. 1.

Fig. 4 is a horizontal section through the lamp, and

Fig. 5 is a front view of the lens of the lamp.

Referring more particularly to the drawings, wherein like characters indicate like and corresponding parts throughout the several views, the supporting base of the lamp is indicated by the numeral 10 and it is preferably constructed of any suitable type of insulating material. A socket 11 of electrical conductive material is attached to the upper surface of the supporting base 10 at the center thereof, and its upstanding sides are threaded for threadably engaging the collar 12 which is carried by the lower end of the shell or sleeve 13. The shell or sleeve 13 is extended in an upright position from the base 10 and it is constructed of any suitable type of insulating material, such as fiber. The threaded collar 12 is attached to the lower end of the insulating shell 13 by rivets or analogous fastening devices as shown at 14. A similar collar 15 is attached at the upper end of the shell 13 and this collar 15 is threaded for connection with the threaded flange or guide 16 of a socket member 17. The socket member 17 is attached by means of rivets 18 and the rivets 18^a to the top 19 of a lamp. The top 19 is constructed of any suitable type of insulating material and is provided with a recess 20 in its under surface and formed centrally therein. The recess 20 receives therein the upper end of a helical spring 21, the lower apex end of which bears against the central contact 22 of the battery structure 23, which battery is contained within the shell 13. The spring 21 is connected to the top 19 of the lamp, by rivets 24 of electrical conducting material which rivets also connect the switch carrying plate 25 to the cover 19, establishing electrical conducting communication between the spring 21 and the plate 25 and consequently between the said plate and the contact 22 of the battery 23. The plate 25 has upstanding guide flanges 26 formed thereon and an upstanding stop flange 27. The guide flanges 26 have their upper edges inturned for engaging the upper edges of the longitudinal ribs formed along the sides of the slidable switch member 28, the sliding movement of which is limited in one direction by the stop flange 27. The sliding switch member or button 28 has a recess 30 in its under surface at its outer forward

edge, which recess is adapted to receive therein the head of a rivet 18^a to establish electrical conducting communications between the contact 22 of the battery, and the 5 socket 17 and collar 15. Electrical conducting communications are established between the collar 15 and the conducting strip 31 which extends along the inner side of the shell 13 by means of a rivet 32 which serves 10 to connect the strip 31 and also the collar 15 to the shell 13. The strip 31 extends downwardly into the lamp bulb receiving socket 32 and is adapted for contact with the central contact 33 of the plug 34 of the 15 lamp bulb 35 to establish communication between one terminal or pole of the lamp bulb and one terminal of the battery. Communication between the other terminal of the lamp bulb 35 and of the battery 23 is established through the contacting engagement 20 of the shell of the plug 34, with the shell of the sockets 36, through a conducting strip 37, which is carried by the shell 13, and through the collar 12, socket 11, and a helical spring 38. The helical spring 38 supports the battery 23, which battery is held 25 against vibratory movement within the shell by a suitable binding strip 39.

A reflector 40 is mounted about the lamp 30 bulb 35 and has a hinged lens carrying ring 41 attached thereto which carries the lens

42. The lens 42 is preferably attached to the ring 41 by a plurality of spaced tongues 43, so as to permit the removal of the lens if desired for replacing a different colored 35 lens in front of the bulb; for instance, when it is desired to use the lamp as a dark room lamp for photographic work, a red lens could be placed in the ring 41, while at other times a white or clear lens would be 40 desirable.

Changes in details may be made without departing from the spirit of this invention, but;

I claim:

In an electric lamp, the combination of a relatively large base, a threaded socket securely attached to said base, a shell of insulating material adapted for engagement with said socket, a lamp socket intermediate the ends of said shell, a top detachably connected to said shell and of smaller diameter than the base, a battery within the shell, helical springs supporting said battery and engaging opposite terminals of 50 said battery for conducting the current, a lamp bulb carried by the lamp socket, means for conveying the current to said lamp bulb, and a switch carried by said top for making 55 and breaking the current.

RALPH OSBORN
